UNITED STATES PATENT OFFICE.

ALFRED BLOSS BELHUMEUR, OF WOONSOCKET, RHODE ISLAND.

STOP-MOTION FOR TWISTING-MACHINES.

1,385,857.

Specification of Letters Patent. Patented July 26, 1921.

Application filed October 27, 1920. Serial No. 420,006.

To all whom it may concern:

Be it known that I, ALFRED B. BELHUMEUR, a citizen of the United States, residing at Woonsocket, in the county of Providence and State of Rhode Island, have invented certain new and useful Improvements in Stop-Motions for Twisting-Machines, of which the following is a specification.

10 This invention relates to twisting and has special reference to a stop motion for twisting machines. The invention more particularly has reference to a stop motion design to operate in connection with a pair of drawing rolls in such manner as to release the thread being drawn between said rolls in the event of breakage of the thread.

One important object of the invention is to provide an improved and simplified construction of stop motion of the character described.

A second important object of the invention is to provide a device of this character wherein the rolls are separated, upon breakage of the thread, by an improved form of lifting mechanism.

A third important object of the invention is to provide, in a lifting mechanism of this kind, a lifting member stamped and formed from a single piece of sheet metal.

With the above and other objects in view the invention consists in general of certain novel details of construction and combinations of parts, as well as improvements in manufacture, hereinafter fully described, illustrated in the accompanying drawings, and specifically claimed.

In the accompanying drawings like characters of reference indicate like parts in the 40 several views, and:

Figure 1 is a side elevation of the improved stop mechanism as applied to a pair of rolls.

Fig. 2 is a transverse section of a portion 45 of the stop mechanism removed from the rolls.

Fig. 3 is a plan view of the stop mechanism removed from the rolls.

In the embodiment of the invention herein illustrated there is shown a portion of a twisting machine of which one of the side frames is indicated at 10. Mounted to rotate between the side frames is a lower roll 11 on top of which operates an upper roll 12 journaled for rotation in guides 13 which

terminate in slotted forks 14 wherein the journals 15 of said roll 12 are mounted. By this means the roll 12 can rotate when in contact with the roll 11 but the roll 12 can also move upward out of contact with said roll 11.

At 16 is a guide eye or loop through which passes the thread 17. Pivotaly mounted on the journals 15 is a lifting member which consists of a single piece of sheet metal having a body portion 18 of substantially rectangular form before bending, the body portion being bent in the form of an arc as clearly shown in Figs. 1 and 2. Extending laterally from the blank from which this body portion is formed is a pair of ears 19 which in the completed article are bent down to lie on opposite sides of the roll 12 and receive the roll journals 15. Between the ears 19 the blank is cut with slits to leave 70 tongues bent to form tubes 20 alined with each other along the median line of the blank so that an arm 21 of wire may extend through these ears or sleeves and have its downwardly bent end 22 enter an opening 23 80 formed in the body 18 whereby the arm is rigidly connected to the lifting member or lifter. On the lower end of this arm is an eye 24 through which the thread 17 passes.

From inspection of Fig. 1 it will be seen 85 that so long as the thread is taut the parts will be held in the position shown in full lines but, should the thread break and thereby be loosened, slackening of the thread will result in the weight of the part 18 causing 90 the lifter to rotate and engage the roll 11. Now since the roll 11 is moving in the direction of the arrow in Fig. 1 the edge of the lifter which contacts with the roll will be drawn in and in consequence the roll 12 will 95 be raised to the dotted line position thereby preventing further movement of the thread 17 while at the same time binding the thread to the roll 11.

There has thus been provided a simple and 100 efficient device of the kind described and for the purpose specified.

It is obvious that minor changes may be made in the form and construction of this invention without departing from the material principles thereof. It is not therefore desired to confine the invention to the exact form herein shown and described, but it is wished to include all such as come within the scope claimed.

Having thus described the invention what is claimed as new, is:—

1. In a machine of the kind described, having a fixed lower roll and an upper roll journaled for vertical movement to and from the lower roll, a lifting device for the upper roll consisting of an arcuate plate provided with inwardly extending ears journaled on the upper roll, and an arm attached to said 10 arcuate plate and provided with an eye at its free end, said arm and plate being arranged to lie on opposite sides of said roll.
2. In a machine of the class described, the

combination with a lower roll mounted for rotation on a fixed axle, an upper roll rotatably mounted above the lower roll and arranged to move vertically to and from the lower roll, a lifter consisting of an arcuate plate covering a segment of the upper roll at one side thereof and having ears journaled on said upper roll, and an arm extending from said lifter on the opposite side of the upper roll and terminating in an eye.

In testimony whereof I affix my signature. 25
ALFRED BLOSS BELHUMEUR.
